[57] CLAIM

The ornamental design for an infusion pump cartridge, as shown and described.

DESCRIPTION

FIG. 1 is a perspective view of an infusion pump cartridge, showing my new design;

FIG. 2 is a top plan view thereof;

FIG. 3 is a side elevational view thereof, the opposite side elevational view being identical thereto;

FIG. 4 is a front elevational view thereof; and

FIG. 5 is a rear elevational view thereof.

The bottom of the article is substantially plain and unornamented.

FIG. 1

FIG. 2

FIG. 3

FIG. 4

FIG. 5
